Filed June 28, 1968, Ser. No. 12,535

Term of patent 14 years

Int. Cl. D1—01

U.S. Cl. D1—18

FIG. 1.

FIG. 2.

FIG. 1 is a front elevational view of a cookie, showing my new design; and

FIG. 2 is a side edge view thereof.

The back of the cookie is conventionally plain.

The essential features of my design reside in the portions shown in solid lines, conventional printed matter being shown in broken lines in FIG. 1.

I claim:

The ornamental design for a cookie, as shown and described.
